UNITED STATES PATENT OFFICE

171,433

QUILTED PLASTIC FABRIC

Abe S. Bloomberg, Swampscott, Mass., assignor
to Bolta Products Sales, Inc., Lawrence, Mass.

Application September 28, 1953, Serial No. 26,964

Term of patent 14 years

(Cl. D87—3)

To all whom it may concern:

Be it known that I, Abe S. Bloomberg, have invented a new, original, and ornamental Design for Quilted Plastic Fabrics, of which the following is a specification, reference being had to the accompanying drawing, forming a part hereof.

Fig. 1 is a plan view of a quilted plastic fabric, showing my new design; and

Fig. 2 is a side elevation taken on line 2—2 of Fig. 1.

I claim:

The ornamental design for a quilted plastic fabric, as shown.

ABE S. BLOOMBERG.
